INVENTOR,
George W. Fleming,
BY
Harry W. Brown.
ATTORNEY.

UNITED STATES PATENT OFFICE.

GEORGE W. FLEMING, OF SPRINGFIELD, MASSACHUSETTS.

TWO-TONED AUTOMOBILE-HORN CONTROL.

1,299,163.

Specification of Letters Patent.

Patented Apr. 1, 1919.

Application filed April 27, 1918. Serial No. 231,075.

To all whom it may concern:

Be it known that I, GEORGE W. FLEMING, a citizen of the United States of America, residing at Springfield, in the county of

5 Hampden and State of Massachusetts, have invented certain new and useful Improvements in Two-Toned Automobile-Horn Controls, of which the following is a specification.

10 This invention relates to improvement in electric switches, and is particularly designed for use in sounding the usual electric horn on automobiles, motor cycles, or trucks for the purpose of giving the necessary 15 warning when the driver of the machine is about to pass another machine or warn a person on the roadway. The loudness of the usual horn is such that oftentimes it does not give sufficient warning to permit the 20 driver of the machine to pass the one ahead of his without involving danger, especially where the roadway is narrow as in the country. This invention embodies a switch, the normal position of which is designed to 25 close an electric circuit so as to sound a horn of ordinary loudness, and, if desired, to close another circuit to permit the same or another horn to be sounded to produce a louder tone, and, after the operator has 30 released his hand, the switch will automatically return to its normal position. The invention broadly comprises a base piece that is designed to fit within the upper end of the steering post, or tube; electric terminals 35 embedded within the base piece, a cap rotatably mounted thereon and having electric terminals embedded therein for contacting with those on the base, and, having means for normally holding the cap elevated for separating the contacts, and means for normally holding the cap in this inoperative position; also means to permit the cap to be rotated, and, when simultaneously moved downward, to close an electric circuit which leads to an 40 other, and louder sounding horn, or to permit a greater flow of current to the same horn, as described.

Referring to the drawings:

Figure 1 is a plan view showing in dotted lines the spring for normally holding the cap in position for sounding the usual horn, when depressed by the operator, also showing the contact terminals.

Fig. 2 is a vertical sectional view on the 55 line 2—2 of Fig. 1, showing the base and

cap-piece in section, the spring for holding the cap piece elevated, and the wires therein and with their coöperating contact terminals separated.

Fig. 3 is a perspective view of the cap, 60 the same being inverted to illustrate the hub and sector shaped pieces formed integral therewith.

Fig. 4 is a horizontal sectional view on the line 4—4 of Fig. 2, showing the expansion 65 spring located in the arc shaped recesses of the base piece, the arc shaped rod, opposite ends of which are located in the base piece, the sector shaped piece on the cap and located in the arc shaped opening of the base 70 and against which the compression spring bears, also the contact arm which is carried by the cap. In the position of the parts shown in this figure, the arm is located above the contact that is connected to the horn 75 for sounding the normal signal, and, shown in dotted lines the other terminal which leads to the same or a different horn for sounding a louder signal.

Fig. 5 is a view showing the contact arm 80 located over the second terminal for sounding the louder horn, and with the cap returning spring compressed.

Fig. 6 is a perspective view of the base piece showing the cut out portion with the 85 opposite shoulders, and the opening in which is fitted a hub of the cap piece.

Referring to the drawings in detail:

1 indicates the upper end of the tubular steering post, 2 the base piece of the switch, 90 3 the hub part of base piece which is fitted into tube 1. The hub 3 is provided with an opening 4 extending therethrough, the upper end of the opening being formed with an annular recess 5, 6 and 7 designate 95 the shoulder portions of the base piece 2 having openings 8 and 9 therein, in which is located the arc shaped rod 10 shown clearly in Figs. 4 and 5. The base piece is provided with contact terminals 11 and 12 to 100 which the wires 13 and 14 are connected, which wires extend downward through the post 1, shown in Fig. 2. 15 designates a cap-piece which is mounted for rotation on the base piece 2 and is formed with a downwardly extending side or flange 16. Formed also integral with or connected through the cap piece 15, is a cylindrical hub 17 which is centrally located as shown in Fig. 2, in the opening 4 of the base piece. Passing 110

through the hub and into the upper part of the cap is an electric terminal 18, to the lower end of which is connected a wire 17 that leads to one of the terminals of a suitable battery or other source of electric energy. The end 20 of the terminal 18 is bent downward and its free end extends slightly below the surface 21 of the cap (see Fig. 3). Located in the annular recess 5 is a coiled expansion spring 22, which normally maintains the cap 15 in the elevated position shown in Fig. 2, and with the end 20 above the contact terminal 11 in the base piece, whereby the electric circuit is normally opened, it being understood that the wire 18 is connected to the usual horn. If the operator wishes to sound the horn, he presses downward on the cap 15 and against the tension of the spring 22, bringing the terminals 20 and 11 together whereby the usual horn device is sounded.

Referring now to the construction and operation of sounding the second horn or alarm, it will be noticed that the cap 15 is provided with a segment shaped block or piece 23, which is connected to or formed integral with the cap as shown in Figs. 2, 3, 4 and 5. The arc shaped rod 10 passes loosely through an opening in the piece 23. Mounted on this rod and between the shoulder 6 and the surface 24 of the piece 23, is an expansion spring 25, the operation of which is to normally hold the block 23 of the cap against the shoulder 7 of the base piece as shown in Fig. 4, and also the cap 15 as a whole so that the terminals 20 and 11 are oppositely located. Should it be desired to sound the louder horn, the operator simultaneously with his pressing 40 downward on the cap 15 against the tension of the spring 22, rotates the cap to the position shown in Fig. 5, thus compressing the spring 25 and moving the contact arm 18 so that the end 20 is over the contact terminal 12 that leads to the louder horn (not shown) thus closing the circuit to the larger horn whereby a signal is sounded of greater loudness than that during normal operation. It is clear that the horn would be 50 blown as long as the operator holds the cap 15 compressed against the tension of the spring 25. Upon releasing his hand from the cap, it is immediately elevated by the spring 22, and returned to its normal position shown in Fig. 14 by the spring 25 with the end 20 of the arm 18 over the contact plate or terminal 11. It is then in position for normal operation, or for sounding the signal of normal loudness. It will be 60 seen from this construction that I have provided a switch for use upon the steering post or other desirable location of a motor vehicle that will permit of sounding the horn of usual loudness or tone and is adapted for ready adjustment for sounding a horn

of different tone as the occasion may arise and at the same time will be held in position for normal operation.

What I claim is:

1. In a switch for the purpose described, the combination with a base piece, annular arranged terminals in the base piece, a rotatable and depressible cap mounted on the base piece, a terminal in the cap designed to contact with one of the terminals in the base piece when the cap is rotated and simultaneously depressed, means for normally retaining the cap elevated and the terminals separated, but designed to be brought into contact when the cap is only depressed for sounding one horn, means to permit the cap to be moved into a position for bringing the terminal in the cap into contact with a second or different terminal in the base piece for sounding a second horn of greater loudness than is sounded when the cap is only depressed, and means for automatically returning the cap to its original position.

2. A switch of the class described, comprising a base piece formed with a cut out portion, a rod located in said portion, a spring mounted on the rod, a cap, a portion attached to the cap and mounted on the rod and against which one end of the spring engages for moving the cap, means for movably supporting the cap on the base piece and for permitting movement against the tension of the spring, spaced electric terminals on the base piece, and a terminal on the cap for coöperating with any one of the terminals in the base piece, whereby the cap may be moved into different positions, to engage any one of the terminals for closing an electric circuit, for the purpose described, and whereby the spring will serve to return the cap and its terminal for normal operation of the switch.

3. A switch for causing the sounding of two electric horns for motor vehicles and comprising a part or base piece, said part having two electric terminals, a cap movably mounted on the said part and having a terminal adapted to register with either one of the terminals of the part or base piece, means for normally holding the terminals in separated positions, means for permitting rotation of the cap to bring the terminal in the cap into a position over either one of the terminals of the part or base piece and means for automatically returning the cap to its first position after it has been moved for registration with either one of the terminals in the base.

4. An electric switch for sounding horns of different pitch on a motor vehicle and comprising, in combination, base and cap members adapted for rotation relative to each other, coöperating terminals in said members, means including an axially arranged spring for normally holding the top

minals separated, means including a spring whose axis is arc-shaped for automatically returning the cap to its normal position for sounding a horn of low tone when moved 5 axially and after having been moved into a position for sounding a horn of higher tone, for the purpose described.

5. An electric switch for closing one or more electric circuits for sounding one or 10 more electric horns, and comprising in combination, a base and cap piece having movement relative to each other coöperating electric terminals in the base and cap, means including an axially arranged spring for 15 normally maintaining the terminals which close the circuit to the horn of low tone open, means including an arc-shaped rod secured to the base piece, a spring thereon engaging the cap and base piece to permit 20 rotation of the cap to a position to permit closure of the terminals of the circuit which

sound the horn of higher tone and for returning the cap to its first or normal position.

6. A switch for the purpose described, 25 comprising a base piece having an arc-shaped cut away portion, a rod secured in said portion, a cap rotatably mounted on the base-piece and having a piece thereon which enters the cut away portion and an opening 30 therethrough to receive the rod, a spring on the rod and located between the segmental piece and a shoulder of the base-piece for maintaining the cap in position for sounding a horn of usual loudness and permitting 35 rotation of the cap into a position for sounding a horn of greater loudness, contacts in base and cap for closure when the cap is depressed, and means for normally maintaining the cap elevated and the contacts separated. 40

GEORGE W. FLEMING.
